UNITED STATES PATENT OFFICE.

CHEEVER C. CONLEE, OF DAYTON, OHIO.

AUDIBLE SIGNAL FOR MOTOR-VEHICLES.

1,348,930.

Specification of Letters Patent. Patented Aug. 10, 1920.

Application filed December 26, 1919. Serial No. 347,282.

To all whom it may concern:

Be it known that I, CHEEVER C. CONLEE, a citizen of the United States, residing at Dayton, in the county of Montgomery and 5 State of Ohio, have invented certain new and useful Improvements in Audible Signals for Motor-Vehicles, of which the following is a specification.

This invention relates to motor vehicles, 10 and the primary object of the invention is to provide an improved means for sounding a warning signal when an unauthorized person or persons starts the engine, thereby reducing the likelihood of a vehicle being 15 stolen to a minimum.

Another object of the invention is to provide an attachment for internal combustion engines of motor vehicles embodying a siren, whistle or the like, adapted to be operated 20 by the exhaust gases of the engine, and so constructed as to be brought into alignment with the exhaust pipe, and locked in such a position so that upon the operation of the engine by unauthorized persons, the 25 siren, whistle or the like, will be operated, thereby calling the owner's attention to the fact that the vehicle is being tampered with.

Another object of the invention is to provide an exhaust operated signal for motor 30 vehicles, which may be locked into operative position by the driver of the vehicle when leaving the machine to provide a theft signal, or which may be operated upon the option of the driver from his seat and used 35 as an ordinary road warning signal.

A still further object of the invention is to provide an improved device of the above character which is durable and efficient in use, one that is simple and easy to manufacture, and one which can be placed upon the market and installed upon a machine 40 at a reasonable cost.

Other objects of the invention will appear in the following detailed description, taken 45 in connection with the drawings, forming a part of this specification, in which drawings:

Figure 1 is a fragmentary side elevation of a motor vehicle showing the improved 50 device applied thereto and in locked position.

Fig. 2 is a vertical longitudinal section through the device.

Fig. 3 is a detail fragmentary section taken on the line 3-3 of Fig. 5.

Fig. 4 is a vertical horizontal section

taken through the device at right angles to Fig. 2, showing the device in signaling position.

Fig. 5 is a front elevation of the device 60 showing the exhaust pipe in section.

Fig. 6 is a view similar to Fig. 4 showing the device in non-signaling position, and for permitting the free flow of exhaust gases through the same, and 65

Fig. 7 is a detail perspective view of the means for operating the device from the driver's seat.

Referring to the drawings, in detail, 70 wherein similar reference characters designate corresponding parts throughout the several views, the letter A indicates the improved device, which is adapted to be associated with the exhaust pipe B of the internal combustion engine C of a motor vehicle D. The means for operating the attachment is designated by the numeral E. 75

The improved attachment A includes a casing 10, which may be attached in any desired position on the exhaust pipe, such 80 as at the intersection of the exhaust pipe with the exhaust manifold tube, or at the intersection of exhaust tube with the muffler, or at the discharge end of the muffler, or in any position upon the exhaust pipe 85 between the engine and muffler. As shown, the casing is connected to the exhaust pipe adjacent to the engine so that the same can be conveniently reached by the operator upon the lifting up of the hood of the motor 90 vehicle.

The casing 10 includes a front and rear plate 11 and 12 having aligned openings 13 formed therein for the passage of the products of combustion therethrough. The 95 front and rear plates 11 and 12 are held in their correct positions by side plates 14, which are arranged intermediate the upper and lower terminals of the side plates and secured thereto by bolts or rivets 15, which 100 also extend through the attaching flanges 16 formed on the sections 17 and 18 of the exhaust pipe B. The flanges 16 formed on the sections of the exhaust pipe surrounds the openings 13 formed in the front and rear plates 11 and 12, and if so desired, packing 105 gaskets may be interposed between the flanges and front and rear plates for preventing the escape of the exhaust gases from the casing. 110

The casing 10 has slidably mounted therein a solid slide block 19 which has its sides

provided with reduced guide ways 20 which define upper and lower shoulders 21 and 22, which are adapted to engage the outer surfaces of the side plates 14, and these 5 shoulders form means for limiting the movement of the slide block in the casing.

The slide block 19 has formed therein a pair of spaced openings 23, and 24, which are adapted to be brought into alignment 10 with the openings 13 formed in the casing at the option of the driver of the motor vehicle. While the openings are spaced from each other, the same are arranged in relatively close relation, so as to not obstruct the passage of the exhaust gases during the sliding of the block in the casing. The upper opening 23 forms means for permitting the free unobstructed flow of exhaust gases through the casing, and the 15 same is normally held in alignment with the openings in the casing by the weight of the slide block, and the downward movement of the block is limited by the upper shoulders 21. 20

25 The lower opening 24 is adapted to receive a siren, whistle or any other preferred type of signal 25, and when the block is in its raised position, the signal is brought into alignment with the openings in the casing, and thus be operated by the exhaust 30 gases. When the block is in its raised position, the lower shoulders 22 engage the lower face of the side plates 14 and thus prevent the openings 24 from being moved 35 out of registration with the openings in the casing.

The lower terminals of the front and rear walls 11 and 12 are provided with aligned apertured ears 26, which are adapted 40 to align with the apertured ear 27 formed on the lower end of the slide block, when the slide block is in its raised position, and when the apertured ears 26 and 27 are in alignment, the same are adapted to receive 45 the shackle 28 of an ordinary or any preferred type of padlock 29.

In operation of the improved attachment, the driver of the vehicle raises the block 19 in the casing 10 when he leaves the motor 50 vehicle and locks the block in its raised position by means of the padlock 29 as heretofore stated, and if a person starts the engine the products of combustion will sound the siren, whistle or the like, and 55 thereby call attention to the fact that the vehicle is being tampered with.

To permit the device to be used as an ordinary signal an operating means E is provided, which includes a foot operated 60 lever 30 arranged adjacent to the driver's seat, and the lever is connected to a suitable link 31, which is provided with an outer forked terminal 32 having slotted arms 33 which slidably and pivotally receive pins 34 65 formed on the sides of the block 19 adjacent

to the upper end thereof. Thus it can be seen by pushing down on the foot lever 30 that the block will be raised and the siren or whistle brought into alignment with the exhaust pipe. Upon the removal of pressure from the foot lever the block 19 will drop to its normal position by gravity. 70

Whether or not the muffler is cut out makes very little difference in operation of the signal. With the muffler cut out the 75 warning would be somewhat louder, but in either case the noise would be sufficient to call attention to the fact that the alarm was being operated and that the car was driven by someone who had no right to do so. 80

The arrangement of the casing 10, the slide block 19, with the exhaust pipe is such that removal of the device from the exhaust pipe is practically impossible, unless the attachment is entirely broken away from the 85 exhaust pipe by the use of a sledge hammer or other heavy instrument.

From the foregoing description, it can be seen that an improved device is provided for internal combustion engines which will 90 effectively prevent the likelihood of a machine being stolen.

Changes in details may be made without departing from the spirit or scope of my invention; but, 95

I claim:

1. In a vehicle road and theft signal, the combination with an exhaust passage of an internal combustion engine, of a casing interposed in the exhaust passage, a slide 100 block carried by the casing, and a signal whistle carried by the block.

2. In a vehicle road and theft signal, the combination with an exhaust passage of an internal combustion engine, of a casing interposed in the passage and having an opening therein for permitting the passage of the exhaust gases therethrough, and an exhaust operated signal arranged in the casing and adapted to be brought into alignment with the openings in the casing. 105

3. In a vehicle road and theft signal, the combination with an exhaust passage of an internal combustion engine, of a casing interposed in the exhaust passage and having an opening formed therein for permitting the passage of exhaust gases therethrough, a slide block mounted in the casing having an opening therein normally aligning with the opening in the casing to 115 permit the free unobstructed passage of exhaust gases through the block, and an exhaust operated signal carried by the block and arranged to be brought into alignment with the opening in the casing. 120

4. In a vehicle road and theft signal, the combination with an exhaust pipe of an internal combustion engine, of a casing interposed in the exhaust pipe, a block slidably mounted in the casing having an open- 125 130

ing formed therein normally alining with the bore of the exhaust pipe, an exhaust operated signal carried by the block and arranged below the opening, means for sliding the block in the casing to bring the signal into alinement with the bore of the exhaust pipe.

5. In a vehicle road and theft signal, the combination with the exhaust pipe of an internal combustion engine, of a casing interposed in the exhaust pipe and having an opening formed therein for permitting the passage of exhaust gases therethrough, a block slidably mounted in the casing, means for limiting the movement of the block in the casing, said block having an opening formed therein normally lying in alinement with the opening in the casing, a signal carried by the block and arranged to be brought into alinement with the opening in the casing upon operation of the block, and means for locking the block against movement when the signal is in alinement with the opening in the casing.

20 6. In a vehicle road and theft signal, the combination with an exhaust pipe, of a casing interposed in the exhaust pipe and having an opening formed therein for permitting the flow of exhaust gases therethrough, a block slidably mounted in the casing, means formed on the block for engaging the casing to limit the sliding movement thereof in the casing, said block having an opening formed therein normally lying in alinement with the opening in the casing for permitting the free unobstructed flow of exhaust gases therethrough, said block having a second opening formed therein normally lying out of alinement with the opening in the casing, an exhaust operated whistle arranged in the second opening, means for raising the block in the casing for bringing the second opening into alinement with the opening in the casing, and removable means for locking the block in its raised position in the casing.

25 7. In a vehicle road and theft signal, the combination with an exhaust pipe of an internal combustion engine, of an attachment therefor including a casing having an opening formed therein for permitting the flow of exhaust gases therethrough, a block slidably mounted in the casing having a opening formed therein normally lying in alinement with the opening in the casing for permitting the free unobstructed flow of exhaust gases through the block, a second opening lying in close spaced relation to the first opening formed in the block, a signal arranged in the second opening, means for sliding the block in the casing for bringing the signal into alinement with the opening formed in the casing, outwardly extending shoulders formed on the upper and lower ends of the block for engaging the casing for limiting the upward and downward

movement of the block in the casing, a foot operated lever operatively connected to the block for raising the same in the casing to bring the signal into alinement with the opening formed in the casing, the block and casing having padlock receiving openings formed therein.

8. In a vehicle road and theft signal, the combination with an exhaust pipe including a pair of sections having flanged terminals, of a casing interposed between the sections of exhaust pipe, means for securing the flanges of the exhaust pipe to the casing, the casing having an opening formed therein for permitting the flow of exhaust gases therethrough, a slide block mounted in the casing having an opening formed therein normally lying in alinement with the opening in the casing for permitting the free unobstructed flow of exhaust gases therethrough, the block having a second opening formed therein, a signal carried by the second opening, a foot operated lever operatively connected to the block and forming means for raising the block in the casing for bringing the signal into alinement with the opening in the casing, the block having a padlock receiving opening formed therein adapted to aline with a padlock receiving opening formed in the casing when the block is in its raised position, and outwardly extending shoulders formed on the upper and lower ends of the block arranged to engage the casing to limit the sliding movement of the block in the casing.

20 9. In a vehicle road and theft signal, the combination with an exhaust passage of an internal combustion engine, of a casing interposed in the exhaust passage, a slide block carried by the casing, and a signal whistle carried by the block arranged to be brought into alinement with the exhaust passage, means for operating the block, and means for locking the block when the signal whistle is in alinement with the exhaust passage.

10. In a vehicle road and theft signal, the combination with an exhaust passage of an internal combustion engine, of a casing interposed in the passage and having an opening therein for permitting the passage of the exhaust gases therethrough, an exhaust operated signal arranged in the casing and adapted to be brought into alinement with the opening in the casing and the exhaust passage, and means for locking the exhaust operated signal in its alined position with the openings in the casing and the exhaust passage.

11. In a vehicle road and theft signal, the combination with an exhaust pipe of an internal combustion engine, of a casing interposed in the exhaust pipe, a block slidably mounted in the casing having an opening formed therein normally alining with the bore of the exhaust pipe, an exhaust oper-

ated signal carried by the block and arranged below the opening, and a foot operated pedal for sliding the block in the casing to bring the signal carried thereby into alignment with the bore of the exhaust pipe.

12. In a vehicle road and theft signal, the combination with a motor vehicle including a foot board, an internal combustion engine having an exhaust pipe, of a casing interposed within the exhaust pipe, a slide block mounted for reciprocatory movement in said

casing, said block having an opening formed therein arranged to normally align with the bore of the exhaust pipe, a signal arranged below said opening and adapted to be brought into alignment with the bore of the exhaust pipe, a foot operated pedal carried by the foot board, and means operatively connecting the foot pedal with the slide block.

CHEEVER C. CONLEE.
